UNITED STATES PATENT OFFICE.

WALTER KIESER, OF BERLIN, GERMANY, ASSIGNOR TO GENERAL ELECTRIC COMPANY,
A CORPORATION OF NEW YORK.

CENTRIFUGAL PUMPING APPARATUS.

1,020,700.

Specification of Letters Patent. Patented Mar. 19, 1912.

Application filed September 2, 1909. Serial No. 515,904.

To all whom it may concern:

Be it known that I, WALTER KIESER, a citizen of Switzerland, residing at Berlin, Germany, have invented certain new and useful Improvements in Centrifugal Pumping Apparatus, of which the following is a specification.

This invention relates to centrifugal pumping apparatus and more particularly to such apparatus for removing the water of condensation and the air, water-vapor and uncondensed gases from condensers.

The object of the invention is the provision of an efficient combined water and air pump of improved construction that is compact, readily balanced as to pressures tending to cause axial movement of the impellers, easily packed against leakage, and that requires fewer stuffing boxes than are necessary when separate pumps are used for performing the same service.

For convenience, in the description which follows the pump which removes the water of condensation will be designated as the water pump and the pump which removes the air, water-vapor and uncondensed gases will be referred to as the air pump.

In the accompanying drawing illustrating one of the embodiments of the invention, Figure 1 is a section of a combined water and air pump on the line 1-1 of Fig. 2; and Fig. 2 is a side view of the pump.

The impeller 3 of the water pump and the impeller 4 of the air pump are mounted in spaced relation on a shaft 5 that is driven by any suitable motor. The air pump is of the throwing type. Water is supplied to the inlet ends of the passages 6 in the impeller 4 by an axially arranged conduit 7. This water is thrown outward by centrifugal action into a series of passages 8 in a guiding or directing ring or member surrounding the periphery of the impeller. The water flows through the passages 8 as a series of liquid pistons between which the air, vapor, etc., from the chamber 9 are entrained. The throwing water and the air are discharged into an annular chamber 10 that conveys them toward a delivery outlet 11.

The inlet conduit 12 at the upper part of the pump casing is connected to the condenser and receives the water of condensation, air, water-vapor, etc., therefrom. The

water of condensation flows along the lower 55 portion of the conduit into a passage 13 leading to a chamber 14 at the center of the pump. From the chamber 14 said water flows into the passages 15 of the impeller 3 and is discharged therefrom into the 60 chamber 16 from which it flows away through a nozzle or nozzles 17. A dam or wall 18 in the lower part of the conduit 12 prevents the water of condensation from flowing over into the chamber 9 where it 65 would interfere with the operation of the air pump. The air, water-vapor, etc., pass along the upper portion of the conduit 12 and through the passage between the dam 18 and the wall of the conduit at the right 70 thereof, Fig. 1, downward into the chamber 9 from which they are drawn into the gap between the impeller 4 and its surrounding guide ring by the action of the throwing water. 75

Since the air and water from the conduit 12 are supplied to their respective pumps from the chambers 9 and 14 near the middle of the apparatus at the same pressure, the absence of a pressure difference renders a 80 special packing between the two pumps superfluous. The stuffing box 19 for the portion of the shaft 5 that projects outward through the casing of the water pump is subjected on one side to the water pressure 85 in the pump casing and on the other to atmospheric pressure. The difference between the two pressures is small and leakage along the shaft is easily controlled. The combined air and water pump also has the 90 advantage that the impeller members are readily balanced against axial thrusts because the oppositely located inner faces of the impellers 3 and 4 are subjected to substantially the same pressure, while the outer 95 face of the impeller 3 is subjected to the pressure of the water of condensation discharged by said impeller and the outer face of the impeller 4 is exposed to the pressure of the throwing water. Thus an equalization of the pressures tending to shift the shaft 5 and the impellers carried thereby axially is easily secured by regulating the pressure of the throwing water. Obviously, multistage pumps could be substituted for 105 the single stage pumps illustrated, if desired.

In accordance with the provisions of the

patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure 10 by Letters Patent of the United States, is,—

1. A combined condensation and air pump comprising a casing, a shaft, a throwing water impeller for the air pump mounted on the shaft, an impeller for the condensation pump mounted on the shaft in spaced relation to the first impeller, means for supplying air and water of condensation to the region between the impellers from which region said fluids pass to their respective impellers, an outlet conduit for the throwing water and air, a delivery conduit leading from the outer side of the condensation pump impeller, and a conduit supplying throwing water to the outer side of the air pump impeller.

2. A combined condensation and air pump comprising a casing, a shaft, a throwing water impeller for the air pump mounted on the shaft, an impeller for the condensation pump mounted on the shaft, a centrally arranged chamber located between the impellers and in communication with the inlet of the condensation pump impeller, 35 means for supplying water of condensation to said chamber, a second chamber outside the first and in communication with the throwing air pump, means for supplying air to the second chamber, an outlet conduit for the throwing water and air, a delivery conduit leading from the outer side of the condensation pump impeller, and a conduit supplying throwing water to the outer side of the air pump impeller.

45 3. A combined condensation and air pump comprising a casing, a shaft, a throwing water impeller for the air pump mounted on the shaft, an impeller for the condensation pump mounted on the shaft, an inlet conduit for the casing which receives air and water of condensation from a condenser, a chamber arranged around the shaft between the impellers and in communication with the inlet of the condensation pump impeller, 50 means for supplying water of condensation from said conduit to the chamber, a second chamber outside the first and in communication with the throwing air pump, means for supplying air from said conduit to the second chamber, an outlet conduit for the throwing water and air, a delivery conduit leading from the outer side of the condensation pump impeller, and a conduit supplying throwing water to the outer side 55 of the air pump impeller.

4. A combined condensation and air pump comprising a casing, a throwing air pump arranged at one side of the casing, a condensation pump arranged at the opposite side of the casing, a shaft on which the impellers of the pumps are mounted, there being a gap between the air pump impeller and its surrounding directing member, an inlet conduit on the upper portion of the casing that receives air and water of condensation from a condenser, a chamber arranged around the shaft between the impellers and in communication with the inlet of the condensation pump, a conduit for conveying water of condensation from the inlet conduit to said chamber, a second chamber outside the first and in communication with the gap of the air pump, a conduit for conveying air from the inlet conduit to the second chamber, means in said inlet conduit 70 for separating the water of condensation from the air and directing them to their respective conduits, an outlet conduit for the throwing water and air, a delivery conduit leading from the condensation pump, 75 and a conduit supplying throwing water to the air pump.

5. A combined condensation and air pump comprising a casing, a shaft, a throwing water impeller for the air pump mounted on the shaft, a directing member within which said impeller rotates, there being a gap between the impeller and said member, an impeller for the condensation pump mounted on the shaft, an inlet conduit on the upper portion of the casing which receives air and water of condensation from a condenser, a chamber arranged around the shaft between the impellers and in communication with the inlet of the condensation pump impeller, a conduit leading from the inlet conduit to the chamber and conveying water of condensation to it, a second chamber surrounding the first and in communication with the gap of the throwing air pump, a conduit leading from said inlet conduit to the second chamber and conveying air to it, a dam in the inlet conduit for preventing the water of condensation from flowing into the conduit leading to the second chamber, an outlet conduit for the throwing water and air, a delivery conduit leading from the outer side of the condensation pump, and a conduit supplying throwing water to the outer side of the air pump.

6. A combined condensation and air pump comprising a casing, a shaft, a throwing water impeller for the air pump mounted on the shaft, a directing member within which the impeller rotates, there being a gap between the impeller and said member, an impeller for the condensation pump mounted on the shaft, an inlet conduit on the upper portion of the casing which receives air and

water of condensation from a condenser, a chamber arranged around the shaft between the impellers and in communication with the inlet of the condensation pump impeller, a 5 second chamber surrounding the first and in communication with the gap of the throwing air pump, a dam extending upwardly from the lower portion of said inlet conduit which forms between it and one wall of the 10 inlet conduit a passage leading from the upper region of said inlet conduit to the second chamber, a conduit leading from the lower region of said inlet conduit between the dam and the other wall of said inlet conduit to 15 the first chamber, an outlet conduit for the throwing water and air, a delivery conduit leading from the outer side of the condensation pump, and a conduit supplying throwing water to the outer side of the air pump.

20 7. A combined condensation and air pump comprising a casing, a condensation pump arranged at one side of the casing, a throwing air pump arranged at the other side of the casing, a shaft on which the impellers 25 of the two pumps are mounted, said shaft having the impeller of the air pump mounted on the end thereof within the casing and projecting outward through the portion of the casing inclosing the condensation pump 30 impeller, means for supplying air and water of condensation at the same pressure to the region between the two impellers, a stuffing box for the projecting portion of the shaft, an outlet conduit in the casing for the 35 throwing water and air, an axially arranged conduit for supplying throwing water to the outer side of the air pump impeller, and a discharge conduit for the water of condensation leading from the outer side of the 40 condensation pump impeller.

8. A combined condensation and air pump comprising a casing, a condensation pump arranged at one side of the casing, a throwing air pump arranged at the other side of 45 the casing, a shaft on which the impellers of the two pumps are mounted, means for supplying air and water of condensation from a condenser to the region between the two impellers so that the inner faces of said 50 impellers are exposed to the same pressure, an outlet for the air and water from the throwing pump, a delivery conduit leading from the outer side of the condensation pump so that the external face of its impeller is subjected to the pressure of the 55 outflowing water, and a conduit for supplying throwing water to the outer side of the air pump so that the external face of its impeller is subjected to the pressure of the 60 throwing water and the thrusts on the shaft due to the pressures on the impellers can be

balanced by varying the pressure of the throwing water.

9. The combination with a centrifugal air pump, of a rotary water pump, and a common conduit means for supplying air to the air pump and water to the water pump. 65

10. The combination with a centrifugal air pump, of a centrifugal water pump, and a common conduit means for supplying air 70 and water of condensation to the air and water pumps respectively, said means including a device for separating the air and water and delivering each to its pump.

11. The combination with a conduit conveying air and water of condensation, of an air pump having an inlet communicating with the upper part of said conduit, and a water pump having an inlet communicating with the lower part thereof. 75 80

12. The combination with a conduit conveying air and water of condensation, of a centrifugal air pump having an inlet communicating with the upper part of said conduit, and a rotary water pump having an 85 inlet communicating with the lower part thereof.

13. The combination with a conduit conveying air and water of condensation and serving to separate the air and water so that 90 the air flows through the upper portion of the conduit and the water through the lower portion, of a throwing-water air pump, a centrifugal water pump, a shaft that is common to the two pumps, means conveying air 95 from the upper portion of said conduit to the air pump, and means conveying water from the lower portion of said conduit to the water pump.

14. The combination with a conduit conveying air and water of condensation and serving to separate the air and water so that the air flows through the upper portion of the conduit and the water through the lower portion, of a throwing-water air pump, a 105 centrifugal water pump, a shaft that is common to the two pumps, means conveying air from the upper portion of the conduit to the inner side of the air pump impeller, means conveying water from the lower portion of 110 the conduit to the inner side of the water pump impeller, a conduit supplying throwing water to the outer side of the air pump impeller, and a conduit conveying the discharge away from the outer side of the 115 water pump impeller.

In witness whereof, I have hereunto set my hand.

WALTER KIESER.
